UNITED STATES PATENT OFFICE.

FRANK R. CHESTER, OF NEW YORK, N. Y., ASSIGNOR, BY MESNE ASSIGNMENTS, TO CHESTERFIELD CONTROL COMPANY, OF DOVER, DELAWARE, A CORPORATION OF DELAWARE.

DISPLAY DEVICE.

Application filed May 27, 1926. Serial No. 111,944.

This invention relates to a display apparatus of improved construction and operation.

It is an object of the invention to provide a device which will possess attractive advertising qualities, and which will embody an extremely simple and economical form of construction operating at minimum expense over long periods of time with freedom from mechanical difficulty and manual attention.

10 It is a further object of the invention to provide a display device the display features of which may be readily renewed when it is desired to do so.

Other objects of the invention will in part 15 be obvious and will in part appear herein-after.

The invention accordingly comprises the features of construction, combination of elements and arrangement of parts which will 20 be exemplified in the construction hereinafter set forth and the scope of the application of which will be indicated in the claims.

For a fuller understanding of the nature and objects of the invention reference should 25 be had to the following detailed description taken in connection with the accompanying drawings, in which

Figure 1 is a plan view of one form of display device embodying the construction of 30 the present invention, the display panel thereof being broken away to disclose the underlying structure;

Fig. 2 is an end elevation of the device as shown in Fig. 1;

35 Fig. 3 is a sectional view of the apparatus as shown in Fig. 2;

Fig. 4 is a plan view of the driving mechanism;

Fig. 5 is a fragmentary partly sectional side 40 view, showing certain details of this mechanism;

Fig. 6 is a transverse view of one of the elements as shown in Fig. 5; and

45 Fig. 7 shows an optional form of drive mechanism.

In these several views the numeral 10 indicates the base of the apparatus, which in its present form simulates in appearance a book opened adjacent its central portion.

50 According to the present embodiment of the invention, brackets 11 and 12 are mounted adjacent the upper and lower book ends and centrally of the side edges thereof, the first bracket supporting a stub shaft 13, and a similar shaft being provided by a screw 14

associated with the second bracket. A split tube 15 extends between these brackets and engages the stub shafts in a manner herein-after specified, this tube supporting a display panel or leaf 16.

60 While any suitable form of leaf-supporting member may be employed, and these elements may be connected in any desirable manner, it is preferred to utilize a split tube, for the reason that by so doing the rear edge of the 65 leaf 16 may be reinforced, for example, by a U-shaped metallic strip 17 having outstanding portions 18, as a consequence of which, when the tube is detached from the book, the leaf or display panel may be readily removed 70 from the tube and replaced, these elements, however, normally being fixed with respect to each other. As shown, the lower end of the tube is screw-threaded for engagement with the threads of the shank of the screw 14, 75 and the upper end of the same receives the stub shaft 13, which carries at its outer end a pin 19. As a consequence, it will be understood that the tube may be readily dismounted by simply detaching the screw 14 and 80 exerting a pull upon the tube towards the lower end of the book, and mounting of the same being accomplished by a reversal of this procedure. When in position the tube will 85 be prevented from movement with respect to the stub shaft 13, and if the latter is oscillated the tube, together with the leaf carried thereby, will be swung back and forth so that the opposite side faces thereof will be displayed alternately.

90 With a view to driving the shaft 13 a motor 20 of any suitable type may be mounted for example, below the base and preferably enclosed within a protective casing 21. This motor rotates a worm shaft 22 by means of 95 a suitable drive 23, this shaft in turn driving a worm wheel 24, which through reduction gearing 25 rotates a crank 26 when the motor is operating. Secured to the outer end of this crank is a rod 27 slotted as at 28, and a crank 29 mounts a pin 30 extending within this slot, this latter crank being in turn secured to a shaft 31 mounting a pinion 32 in mesh with a gear 33 secured to the shaft 13.

100 As a result, it will be understood that when the motor 20 is energized the crank 26 will rotate, reciprocating the rod 27, which, during the final stages of its stroke in one direction, will have the end wall of the slot 28 contacting with the pin 30, thus rocking the 105 110

crank 29 in one direction, and which, further, during its final stages of movement in the opposite direction, will engage similarly the pin of the crank 29 to return it to its initial position. Thus, with the motor operating continuously, the pinion 33 and the shaft 13 secured thereto will be oscillated in such a manner that the leaf connected with the shaft will have its first face displayed for a sufficiently long period of time for the observer to peruse the advertising matter displayed upon said face. Subsequently, the panel will be swung quickly and the rear face thereof will be displayed in a manner similar to the first face. During such periods of display it will be obvious that lost motion will be occurring between the crank and the slot of the rod 27.

If desired, both of the upper faces of the base 10 may simulate in appearance the pages of a book, or, as has been shown, one of the halves of the base may be recessed suitably as at 34 to provide what is commonly known as a shadow box, which may be suitably illuminated. Where a construction of this nature is utilized the display panel or leaf acts as a cover for the shadow box, alternately concealing and revealing the same, together with any article or articles which may be displayed therein.

If it is desired to incorporate a number of leaves or display panels in an apparatus of this nature, this may be readily accomplished by providing a plurality of shafts 35, as in Fig. 7, each corresponding to the stub shaft 13, and mounting gears 36 one upon each of these shafts. The teeth of these gears are interrupted and they are engaged by the teeth 37 of the pinion gear 38, the latter in the present embodiment having the major portion of its periphery unformed, and the series of teeth being just sufficient to assure a proper operation of the shafts 35. It will be obvious that as the shaft 31 which supports the pinion 38 is moved in one direction, the first gear 36 will be turned, carrying with it its shaft, subsequently to which the operation of the second and third pinions follows. Upon the shaft 31 reversing its direction of rotation, the gears 36 will be returned to their initial position, carrying with them the leaves connected with their shafts 35. It is here to be noted that the unformed periphery of the pinion 38 preferably cooperates with recessed portions formed immediately to the rear of the series of teeth in the pinions 36. As a consequence, the latter, when their teeth are not engaged by the teeth 37, are locked against movement.

In both of the illustrated forms of the invention the display panel or panels are turned and re-turned, and this is accomplished in a manner consistent with the objects specifically enumerated previously.

Since certain changes may be made in the above construction, and different embodiments of the invention could be made, without departing from the scope thereof, it is intended that all matter contained in the above description or shown in the accompanying drawings shall be interpreted as illustrative and not in a limiting sense.

It is also to be understood that the following claims are intended to cover all of the generic and specific features of the invention herein described and all statements of the scope of the invention which as a matter of language might be said to fall therebetween.

Having described my invention, what I claim as new and desire to secure by Letters Patent is:

1. A display apparatus in the nature of a book, including a base, a display panel in the nature of a page swingingly mounted upon said base, and means for swinging said panel to alternately display opposite faces thereof, said means embracing a driving member, a driven member connected with said panel, and means providing a pin and slot connection between said driving and driven members, said pin riding within said slot during the periods of display of the opposite faces of said panel, and moving with the member within which the slot is formed during the swinging of said panel.

2. A display apparatus in the nature of a book, including a base, a display panel in the nature of a page swingingly mounted upon said base, and means for swinging said panel to alternately display opposite faces thereof, said means comprising a driving member, a slotted rod, and a pin-carrying crank, the pin thereof riding within said slot, one of said last-named elements being connected with said panel, the other of the same being connected with said driving member.

3. A display apparatus in the nature of a book, including a base, a shaft carried by said base, a display panel in the nature of a book-page connected with said shaft and to be swung thereby to alternately display its opposite faces, a crank connected with said shaft, a slotted rod, means for reciprocating the latter, and a pin carried by said crank and riding within the slot of said rod.

4. A display apparatus in the nature of a book, including a base formed with a display recess, a panel in the nature of a book-page swingable to a position covering the face of said recess, and means for swinging said panel to alternately cover and uncover the face of said recess.

5. A display apparatus in the nature of a book, including a base formed with a recess, a display panel in the nature of a book-page swingingly mounted upon said base and to one side of said recess, and means for moving said panel to alternately display oppo-

site faces thereof and to cover and uncover the face of said recess.

6. A display apparatus, including a base, a slotted tube mounted for oscillation upon said base, means for driving said tube, a sheet, a strip attached to the rear edge of said sheet and extending into said tube through the slit thereof, and offset portions forming a part of said strip and engaging the inner face of said tube.

7. A display apparatus, including a base, a shaft, means for oscillating said shaft, a tube, with one end of which said shaft is detachably connected, and a display panel connected to said tube.

8. A display apparatus, including a base, a pinion formed with a series of teeth, means for oscillating said pinion, a plurality of driven shafts, pinions attached to each of the same and arranged adjacent said first-

named pinion, and display panels associated with said shafts.

9. A display apparatus, including a base, a pinion formed with a series of teeth, means for oscillating said pinion, a plurality of driven shafts, pinions attached to each of the same and arranged adjacent said first-named pinion, display panels connected to said shafts, and means forming a part of said pinions for normally preventing a movement of the driven shafts.

10. A display apparatus in the nature of a book, including a base, a panel in the nature of a book-page swingingly mounted upon said base, and means for swinging said panel to display alternately opposite faces thereof, the periods of display of each face being substantially equal and relatively protracted.

In testimony whereof I affix my signature.
FRANK R. CHESTER.
